United States Patent Office.

WILHELM C. A. THIELEPAPE, OF SAN ANTONIO, TEXAS.

Letters Patent No. 89,256, dated April 20, 1869.

IMPROVEMENT IN NEEDLE-THREADERS FOR SEWING-MACHINES.

The Schedule referred to in these Letters Patent and making part of the same.

To all whom it may concern:

Be it known that I, WILHELM C. A. THIELEPAPE, of San Antonio, in the county of Bexar, and State of Texas, have invented a new and useful instrument, to wit, a Sewing-Machine Needle-Threader; and I do hereby declare that the following is a full, clear, and exact description of the construction and operation of the same, which will enable others skilled in the art to make and use the same, reference being had to the accompanying drawings, forming part of the specifications, in which—

Figure 1 represents an elevation of the front side.

Figure 2, the same applied to the needle.

Figure 3 represents an elevation of the opposite side.

Figure 4 represents an elevation of the side faced to the operator, applied to the needle.

Figure 5 represents a top view.

Figure 6 represents a sectional elevation.

Figure 7 represents a perspective view.

Figure 8 represents a sectional elevation through the eyelet-frame *a*.

Figure 9 represents a detached perspective view of the spring *e*.

Similar letters of reference indicate like parts.

This invention relates to a construction of devices for the purpose of facilitating the passing of a thread into the eye of a sewing-machine needle, and is constructed so that it may be applied to any sewing-machine whose needle may be curved, like that of Wheeler & Wilson's, or straight, like those of Singer's, and others.

a represents the eyelet-frame, formed of two equal parallelopipeds, which, being kept together by the action of the springs *b*, *b*, may be separated by pressing the pins *u* and *v* toward each other.

It is further provided with a conical eyelet, *c*, *d*, as shown in the figs. 1, 3, 6, 7, and 8, the axis of which lies in the joint planes of the parallelopipeds, its apex, *d*, in the front side, its basis, *c*, in the opposite side of the eyelet-frame, through which eyelet the thread has to pass when the instrument is used and applied to the machine-needle, in the manner as will be explained hereafter, and as is shown in figs. 2 and 4.

The adjusting-plate *r* serves to adjust the instrument, so as to suit both the form of the machine-needle *p*, and the distance of its eye from the under end of the needle-arm *g* of the sewing-machine.

For this purpose the adjusting-plate *r* is movable, by loosening the screw *s*, which acts on the pivot *t*, that supports the adjusting-plate, and works loosely in the hole provided for it in the centre of the top-piece *m*. Thus the distance from the eyelet *d* up to the top of the adjusting-plate *r* can be made exactly corresponding with the distance from the needle's eye up to the end of the needle-arm *g*.

To answer the form of the needle, the adjusting-plate is provided with a semicircular notch at each of two opposite edges, as shown in the figs. 1, 2, 3, 5, 6,

and 7, of which the notch *n*, made in the middle of the one edge of the adjusting-plate, is to be put at the front side of the instrument, (by turning the adjusting-plate about its pivot *t*), in case the sewing-machine works with a straight needle; and the notch *o*, made in the opposite edge of the adjusting-plate, a little aside of its middle, is to be put at the front side of the instrument, in case a curved needle is used, as is shown in fig. 2 of the drawings.

Either of these notches serves to receive the machine-needle close to the needle-arm.

The groove *i*, cut in the front side of the eyelet-frame *a*, at the joining-line of the two parallelopipeds, as shown in the figs. 1, 2, 6, and 7, its sectional shape being shown in fig. 8, serves to receive the lower end of the machine-needle, and thus places the eyelet *d* of the instrument exactly in line with the eye of the machine-needle, provided the instrument is properly adjusted, as above mentioned.

The spring *e* serves, when moved on the needle, as shown in the figs. 2, 4, and 5, to fasten the instrument to the needle of the sewing-machine. It therefore can be turned in a plane parallel to the front side of the eyelet-frame *a* about its one end, which passes loosely through a hole provided for it in the eyelet-frame, and thus either be put in the position as shown in the figs. 1 and 7, or in that as shown in the figs. 2, 3, 4, and 5.

Above the dotted line marked *w x*, (see figs. 1 and 6,) the surface of the eyelet-frame is cut away, so as to allow the spring *e* to act equally as well on a fine as on a coarse needle.

In using the instrument, it is necessarily first to be adjusted, by putting that notch of the adjusting-plate *r* at the front side of the instrument that is adapted to the form of the machine-needle, as above explained, and by making the distance from the eyelet *d* up to the top of the adjusting-plate equal to the distance from the needle's eye up to the needle-arm of the sewing-machine, observing that the spring *e* be in the position as shown in figs. 1 and 7. This done, apply the instrument, with its front side to the machine-needle, so that the upper end of the needle, close to the needle-arm, be placed in the appropriate notch of the adjusting-plate, and the lower end of the needle in the groove *i* of the eyelet-frame, and move the spring *e* on the needle, as shown in fig. 2. The eyelet of the instrument will thus coincide with the eye of the machine-needle, and the instrument be fastened, so as to enable the operator to make use of both hands for the purpose of twisting the end of the thread to a point, and entering the same by the left hand into the eyelet at *c*. The thread being guided by the conical form of the eyelet, will pass through the eye of the machine-needle, and can now be caught by the right hand of the operator and drawn through.

Having thus succeeded with the main object, the thread runs now through both the eye of the machine-needle and the eyelet of the instrument, from which it

can easily be detached by pressing, with thumb and fore-finger of the left hand, the knobs of the pins *u* and *v* toward each other, and by removing at the same time, with the right hand, the spring *e* from the needle into its former position.

The action of the pins *u* and *v* will effect the separation of the parallelopipeds, of which the eyelet-frame *a* is formed, as shown in fig. 7, and thereby release the thread, and the removal of the spring *e* from the machine-needle will allow the instrument to be taken away, while the thread remains in the eye of the machine-needle.

The instrument can be easily adjusted to the needle of the sewing-machine, by loosening first, the screw *s*, and allowing the adjusting-plate *r* to rest on the top-piece *m*, observing that the notch answering the form of the needle be at the front side of the instrument.

Fasten the instrument to the machine-needle, as above explained, pass a very fine needle or pin through the eyelet *c* toward the needle of the sewing-machine, move the instrument slowly down, until the fine needle or pin passes into the eye of the machine-needle.

Keeping the instrument in this position, move the adjusting-plate *r* upward, close to the needle-arm of the sewing-machine, and fix it by the screw *s*.

Thus the instrument once adjusted, (the form of the needle as well as the distance of its eye from the needle-arm being invariably the same at the same machine,) the whole manipulation of applying the instrument to the needle, and passing the thread into its eye, is done in half a minute, no matter whether the eye of the needle be large or small, while persons, even tailors,

very often lose ten or more minutes of costly time by the old and tedious mode.

The instrument once adjusted to a sewing-machine, can also be used to advantage for the purpose of setting in a machine-needle, by fastening first, the needle to the instrument, so that its eye coincides with the eyelet of the instrument, and then setting the upper end of the needle into the needle-arm as far as the adjusting-plate allows it, and fix the needle as usual.

The employment of a fine needle passed through the eyelet and the eye of the machine-needle, in performing this operation, will facilitate the same.

It remains yet to be added that each of the pins *u* and *v* runs loosely through a hole provided for in that one of the parallelopipeds which is next to the pin's knob, and fastened to the opposite one, as shown in the fig. 7.

Having thus described my invention, I claim as new, and desire to secure by Letters Patent—

The eyelet-frame *a*, in combination with the springs *b* *b*, for keeping the parallelopipeds together, and the pins *u* and *v* for separating them, the spring *e*, for attaching the device to the machine-needle, and the adjusting-plate *r*, with its notches *n* and *o*, adapted for a curved or a straight needle, all constructed and operating substantially as and for the purpose described.

San Antonio, Bexar county, Texas, February 11, 1869
